UNITED STATES PATENT OFFICE.

SYLVA L. DICKSON, OF SHORT CREEK, WEST VIRGINIA.

RELAY SOUNDER ATTACHMENT.

1,105,761.

Specification of Letters Patent.

Patented Aug. 4, 1914.

Application filed September 2, 1913. Serial No. 787,624.

To all whom it may concern:

Be it known that I, SYLVA L. DICKSON, a citizen of the United States of America, and resident of Short Creek, county of Brooke, 5 and State of West Virginia, have invented certain new and useful Improvements in Relay Sounder Attachments, of which the following is a specification.

This invention relates broadly to telegraphic sounders, and specifically to a combined relay and sounder.

The primary object of the invention is to provide in connection with a telegraphic relay of an ordinary type a simple and efficient form of sounder actuated directly by the relay and not requiring the interposition of a local circuit with its attendant batteries and wiring connections.

A further object is to provide a sounder 20 having means of adjustment whereby the magnitude of sound propagated therein may be regulated.

With these and other objects in view, the invention resides in the features of construction, arrangement of parts and combinations of elements which will hereinafter be fully described, reference being had to the accompanying drawings, forming a part of this specification, in which—

30 Figure 1 is a top plan view of the invention; Fig. 2 is a side elevation of the same; Fig. 3 is a partial cross section taken substantially on the line 3—3, Fig. 2; and Fig. 4 is a longitudinal section of the same.

35 Referring to said drawings, in which like designating characters distinguish like parts throughout the several views—1 indicates the base, 2 the magnet coils, 3 the binding posts, 4 the armature-withdrawing spring, 40 5 the spring-tension adjusting screw, 6 the supporting post, and 7 the adjustable screw-supporting rod of an ordinary type of telegraphic relay, all of said parts being of a common form.

45 A pivoted armature 8 arranged to coöperate with the electromagnet has an upright arm or lever 9 formed integral therewith, as shown, and disposed at opposite sides of said arm or lever are two substantially circular metallic disk-like diaphragms 10 and 11. Each of said diaphragms has projected inwardly from its center a stud or pin 12, said pins constituting stops between which the upper end of said lever plays as the armature 8 is attracted by the electromagnet or withdrawn by the spring 4, and by the

striking of which a clicking sound is produced. Said diaphragms 10 and 11 are respectively supported by plates 13 and 14, peripheral flanges 13' and 14' formed on said plates being disposed in embracing relation to said diaphragms. Strips of insulating material 15 and 16 are interposed between the peripheries of said diaphragms and the flanges of the plates, as shown. Said plates 65 13 and 14 are peripherally embraced and supported by a casing 17 having integral extensions 17' constituting supporting legs that are rigidly mounted upon the base 1. The plate 13 is rigid with respect to the 70 casing 17, while plate 14 is movable with respect to said casing. Thus, the distance between the stops 12 may be adjusted for increasing or decreasing the length of stroke of the lever 9, providing for the regulation 75 of the volume of sound emitted upon the contact of the lever with said stops.

Fixed in the flange 14' is a plurality of pins or screws 18 each of which projects outwardly through and is slidable in an 80 inclined slot 19 provided in the casing 17. One of said pins or screws is preferably in the form of a set-screw, as 18a, adapted to be set, when in adjusted position, in impinging relation to the casing for binding 85 the plate 14 in fixed relation to said casing. As is obvious, a slight rotation of the plate 14 acts to cause the diaphragm 11 to approach or move away from the diaphragm 10, according to the direction of said rotation. For the purpose of allowing the volume of sound emitted by the striking of the 90 arm or lever 9 against the stops carried by the diaphragms to escape unobstructedly, openings or slots, as 20, are provided in the 95 casing 17, and outwardly directed tubular extensions 21 are provided centrally of the plates 13 and 14.

Fixed, as by soldering, to that face of the armature 8 which is next to the magnet 100 coils 2 is a downwardly extending flat spring 22, the lower end of which, in the movement of the armature toward said coils, engages the point of a regulating screw 23 just prior to the limit of said movement being reached. And, due to the slight flexure given said spring in said movement, said armature, when released, is quickly thrust back to its normal position, said spring 22 serving to assist the withdrawing spring 4 110 and to accelerate the return movement of the armature, while offering no resistance.

to the armature during the initial and major portion of its forward movement.

From the foregoing it will be understood that I provide, in connection with a relay of a common type, a simple and efficient sounding device which renders unnecessary the attachment of a separate sounder in a local circuit with its attendant batteries. However, should a local circuit be found desirable, the same may be connected through the usual binding posts 24 provided on the relay base 1.

Having thus described my invention, what I claim as new, and desire to secure by Letters Patent, is—

1. The combination with a telegraphic relay having an armature provided with an upright arm, of a pair of metallic diaphragms disposed on opposite sides of said arm and adapted to be struck by the latter at the limits of its movements for producing audible sounds, plates supporting said diaphragms, and a casing supporting said plates, one of said plates being adjustably mounted within said casing.

2. The combination with a telegraphic relay having an armature provided with an upright arm, of a pair of metallic diaphragms disposed on opposite sides of said arm and adapted to be struck by the latter at the limits of its movements for producing audible sounds, plates supporting said dia-

phragms, and a casing supporting said plates, said casing having inclined slots therein, pins carried by one of said plates and projecting outward through said slots whereby a rotary movement imparted to the plate acts to advance or retract the latter with respect to the other plate, according to the direction of said movement.

3. The combination with a telegraphic relay having an armature provided with an upright arm of a pair of metallic diaphragms disposed on opposite sides of said arm and adapted to be struck by the latter at the limits of its movements for producing audible sounds, plates supporting said diaphragms, a casing supporting said plates, said casing having inclined slots therein, pins carried by one of said plates and projected outward through said slots whereby a rotary movement imparted to the plate acts to advance or retract the latter with respect to the other plate, according to the direction of said movement, and means for securing said movable plate in adjusted position.

In testimony whereof, I affix my signature in presence of two subscribing witnesses.

SYLVA L. DICKSON.
